UNITED STATES PATENT OFFICE.

HENRY T. PLATZ, OF DETROIT, MICHIGAN, ASSIGNOR TO C. M. HALL LAMP CO., OF DETROIT, MICHIGAN, A CORPORATION OF MICHIGAN.

TILTABLE REFLECTOR.

1,416,749.

Specification of Letters Patent. Patented May 23, 1922.

Application filed November 20, 1920. Serial No. 425,303.

To all whom it may concern:

Be it known that I, HENRY T. PLATZ, a citizen of the United States of America, residing at Detroit, in the county of Wayne 5 and State of Michigan, have invented certain new and useful Improvements in Tilt-able Reflectors, of which the following is a specification, reference being had therein to the accompanying drawings.

10 The invention relates to headlights for motor vehicles and has for its object the provision of means for tilting the reflector. It is a further object to obtain a simple construction of mechanical operating means and 15 one which will not distort or in any way injure the reflector or other delicate parts of the device. Still further, it is an object to obtain a simple and inexpensive construction to manufacture, as hereinafter set forth.

20 In the drawings:

Figure 1 is a vertical central section through the headlight;

Figure 2 is a horizontal section on line 2—2 of Figure 1;

25 Figure 3 is a sectional front elevation.

A is a bracket or support for the lamp body, which is formed with a hollow shank B containing the plug socket C for the electrical conductor. D is a segmental head 30 plate on the bracket A which fits the inner surface of the sheet metal housing E forming the body of the lamp and which is secured thereto by the rivets F or other suitable means. The bracket A also has an inwardly projecting lug F' forming the fulcrum for a bell crank lever G, one arm of which extends in operative relation to a push rod H, slidably engaging a bearing I in the rearward extension J of the bracket A.

40 Within the housing E is arranged a parabolic reflector K. This is pivotally mounted on trunnions L upon diametrically opposite sides of the casing, which trunnions preferably consist in shoulder screws which engage 45 brackets M secured to the sides of the housing. The connection between the trunnions and the parabolic reflector is formed by eyebolts N engaging the shoulder screws L and having forwardly projecting threaded and 50 pointed shanks O, which pass through apertures in the outwardly-extending flange P on the reflector. A washer Q and nut R engaging the shanks O serve to clamp the eyebolts to the flange P. S is a spring 55 washer sleeved upon the shoulder bolt L

between the head of said bolt and the outer face of the eyebolt, this serving to cause sufficient friction to hold said eyebolt in its normal position of angular adjustment. T is a link, one end of which is pivotally connected to the bell crank lever G, while its opposite end is pivotally connected to a bracket U secured to the lower central portion of the flange P of the reflector. V is a spring extending between the pivot pin 60 W, which connects the link T to the bracket U, and the pivot pin X which connects the bell crank lever G with the fulcrum lug F'. With the construction as described the reflector K is capable of an oscillatory move- 65 ment upon the trunnions L and its angular position is determined by the position of the bell crank lever G and link T. Normally, the tension of the spring V will hold the bell crank lever against the push rod H, 70 which latter has a head H' for engaging the bearing I. If, however, pressure is applied to the rod H, it will be moved inward and by rocking the bell crank lever G will tilt the reflector.

75 As specifically shown, the parts are so arranged that the tension of the spring V holds the reflector to the limit of its downward tilting movement, in which position the projected rays of light will illuminate 80 the road in front of the car, but will not extend upward at a sufficient angle to be objectionable to travelers headed in the opposite direction. To facilitate the setting of this angle, the bearing I is adjustable 85 in the bracket A, preferably by externally threading it so that it may be screwed inward or outward in said bracket, while the lock nut I' serves to hold it in any position of adjustment.

90 The casing E is provided with the usual hinged door, such as Y, which is preferably hinged at Y' at the top and is provided at the bottom with a lock Y². The latter is formed by a lug Y³ projecting forward 100 from the bracket A and downward through a slot in the casing E, said lug being slotted to engage the shank of a clamping bolt and the adjustable nut Y⁴ thereof. The lamp socket Z is mounted upon the reflector to be movable therewith and is connected by a flexible conductor Z' with the lamp terminal socket C.

105 To form a finish about the reflector in its various positions of adjustment, the flange 110

P is surrounded by a cylindrical flange P', which is secured by the screws P² to an inwardly-extending flange E' on the casing E. The cylindrical flange P' extends a sufficient distance to cover the edge of the flange P in its farthest tilted position. This will produce a finish in all positions of adjustment and by making the inner surface of the flange either opaque or with a diffusing surface, any glaring upward deflection of the light therefrom is avoided.

One of the advantages of the construction is that all the parts of the adjusting mechanism are mounted upon the single bracket A so that when once properly adjusted in relation to each other, there is no chance for them to become disarranged. Another feature is that the tension of the spring V, which is employed for actuating the tilting reflector in one direction, does not produce any stress on said reflector which might tend to distort it from its true parabolic form. Still another feature of advantage is the easy means of adjusting the normal position of the reflector, which is accomplished by loosening the nut I' and turning inward or outward the threaded bearing I. This adjustment also permits of setting a pair of lamps so that they will be properly aligned with each other, even where the supporting brackets for said lamps may be out of true alignment.

While I have specifically shown the lamp as held normally to the limit of its downward tilting movement, it is obvious that the reverse could be accomplished by suitable modification of the lever connections.

To facilitate access to the electrical connections at the back of the reflector, the latter can be readily detached at any time from its trunnions L. Thus by removing the nuts R and washers Q, the reflector may be tilted outward, turning upon the pivot W. In doing this the eyebolts O will be

frictionally held by the tension of the spring S from angular movements, so that the reflector can be readily re-engaged with said eyebolts when desired.

What I claim as my invention is:

1. In a lamp, the combination with an outer casing, of a reflector therein, a link connected to said reflector for tilting the same, trunnions mounted upon the inner walls of said casing forming a pivotal bearing for said reflector, a bearing engaging each trunnion having a forwardly extending threaded shank for engaging an aperture in a flange on said reflector, means for resisting rotation of said bearings, and a clamping nut for engaging said threaded shank. 60

2. In a lamp, the combination with an outer casing, of a reflector therein, mechanism connected to said reflector for tilting the same and a pivot bearing for said reflector comprising trunnions mounted upon the inner walls of said casing, a bearing on said trunnion having a forwardly extending threaded shank registerable with an aperture in the flange of said reflector, friction means for resisting rotation of said bearing and shank on said trunnions to hold the same in registration with said apertured flange when detached therefrom to facilitate replacement, and clamping means for engaging said threaded shank to secure the same 75 to said apertured flange.

3. In a lamp, the combination with an outer casing provided with brackets detachably secured upon diametrically opposite sides thereof, of a rockable reflector within said casing, an eye-bolt detachably secured to said reflector and forming a pivotal mounting therefor upon said bracket, means for actuating said reflector, and means for normally holding the same in predetermined 80 position.

In testimony whereof I affix my signature.
HENRY T. PLATZ.
